UNITED STATES PATENT OFFICE.

STEPHEN S. NEWTON, OF BROOKLYN, NEW YORK.

DESIGN FOR A BOTTLE-STOPPER.

SPECIFICATION forming part of Design No. 18,105, dated February 21, 1888.

Application filed January 4, 1887. Serial No. 223,404. Term of patent 14 years.

To all whom it may concern:

Be it known that I, STEPHEN S. NEWTON, a citizen of the United States, residing at Brooklyn, in the county of Kings and State of New York, have invented a certain new and original Design for Bottle-Stoppers, of which the following is a specification, reference being had therein to the accompanying drawing.

My invention relates to a novel design for a stopper adapted to close bottles, flasks, and similar articles.

The design consists in the stopper or upper part thereof in the shape of a tulip.

This design may be given to whatever material is used to form the stopper, and represents, essentially, a flower-shaped cap for the stopper, and this cap may be made in the shape of a deep cup, with the petals B or C, or both, of different heights and in two rows projecting upward from the base A. The edge of the flower or the ends of the petals will form a

scalloped circumference to the rim or flange around the cup.

I am aware of Design Patent No. 7,871, for an inkstand, and do not claim anything there- 25 in shown.

I am aware of Design Patent No. 1,096, to Smith, and do not claim anything therein shown; but

What I claim is—

The design for bottle-stoppers herein shown and described, consisting of a rim or flange around the cap in the form of the petals of a flower, said petals extending outward from the neck of the stopper as from a stem. 30

In testimony whereof I affix my signature in presence of two witnesses.

STEPHEN S. NEWTON.
